UNITED STATES PATENT OFFICE.

LUTHER B. DAVIS, OF MALDEN, MASSACHUSETTS.

LACING-STUD.

No. 901,694.

Specification of Letters Patent.

Patented Oct. 20, 1908.

Application filed March 7, 1908. Serial No. 419,616.

To all whom it may concern:

Be it known that I, LUTHER B. DAVIS, a citizen of the United States, residing at Malden, in the county of Middlesex and 5 State of Massachusetts, have invented new and useful Improvements in Lacing-Studs, of which the following is a specification.

This invention relates to improvements in lacing studs or hooks for boots, shoes, 10 gloves, corsets and the like in which a lacing is used as a fastening means, and the object is to provide a lacing hook which when the lacing is laced up cannot catch garments, lace and the like, and the object is further 15 to provide a hook of the character described which shall be thoroughly practical, durable and easy to manufacture.

The invention consists in the combination and arrangement of parts set forth in the 20 following specification and particularly pointed out in the appended claims.

Referring to the drawings: Figure 1 is a central sectional elevation of a lacing stud or hook embodying my invention, the same 25 being shown inserted in a hole in a piece of sheet material but without the shank being clenched, this view showing the hook open to receive a lacing. Fig. 2 is a sectional elevation similar to Fig. 1 but with the hook 30 closed. Fig. 3 is a detail plan section taken on line 3—3 of Fig. 1. Fig. 4 is a perspective view showing a portion of the upper of a boot with a series of hooks embodying my invention attached thereto, part of the hooks 35 being closed with a lacing therein and the remaining hooks being open. Fig. 5 is a central sectional elevation of a modified form of hook or stud constructed in accordance with my invention. Fig. 6 is a plan 40 section taken on line 6—6 of Fig. 5.

Like numerals refer to like parts throughout the several views of the drawings.

In the drawings, referring now to Figs. 1 to 4, inclusive, 10 is a base which may be 45 of any suitable form, but which in this instance is provided with a tubular shank 11 and an annular flange 12, said base being adapted to be secured to a piece of sheet material 13 by forcing said shank there- 50 through and clenching said shank on the underside of said sheet material in a well known manner. In the drawing the shank is shown before such clenching.

Slidably mounted on the base 10 is a hook 55 14 which in this instance is adapted to slide in a curved path about a center A. The

hook 14 is substantially U-shaped in form having two arms 15 and 16, the arm 16 being connected to the base 10 and held in sliding contact therewith by means of two lugs or 60 projections 17, 17 extending part way thereacross, said lugs being preferably formed by punching two opposite portions of the metal of the shank 11 inwardly toward each other. To form a support on which the arm 16 may 65 slide, I provide two lugs 18, 18 which may be formed by punching two oppositely located portions of the shank 11 inwardly and giving them a form substantially concentric with the arm 16.

When the hook 14 stands in the position shown in Fig. 1, the same is adapted to receive a lacing therein. When the lacing is drawn against that portion of the hook 14 which is opposite to the opening, said hook 75 is moved thereby into its closed position as shown in Fig. 2 and as illustrated also in the two lower pairs of hooks in Fig. 4. Thus it will be seen that while the boot or the like is laced up the hooks are closed and there is 80 nothing which can catch on the garments of the wearer.

In order to limit the extent of sliding movement of the hook 14, I provide a stop 19 which may be formed on said hook by 85 striking or forming downwardly on the arm 16 a projection which is adapted to engage one of the lugs 18 when the hook is in its open position and the other of said lugs when the hook is in its closed position.

It will be noted that the outer or upper face of the base 10 is substantially flush with the outer face of the sheet material 13 in which the same is fastened, the hook 14 being the only part of the stud which projects a substantial distance above the outer face of the material. In unlacing the shoe, the lacing is pulled toward the free ends of the arms 15 and 16 and said lacing acting on the arm 15 rocks the hook 14 in an obvious manner from the position shown in Fig. 2 to the position shown in Fig. 1, whereupon said lacing passes outwardly from said hook.

Referring now to Figs. 5 and 6 wherein 105 a modified form of stud constructed in accordance with my invention is illustrated, 10' is a base provided with a shank 11' and an annular flange 12', the metal forming the head of the base being punched downwardly 110 forming two projections 18', 18' and leaving a bridge 17' extending across the base 10'.

The hook 14' is identical in form with the hook 14 of the form of my invention first described and is provided with two arms 15' and 16', the arm 16' being located beneath the bridge 17' and being adapted to slide on the projections 18', there being a projection 19' adapted to limit the extent of sliding movement of said hook as in the case of the form first described. The operation of this form of my invention is similar to that of the form first described and a description of its operation will be unnecessary.

Having thus described my invention, what I claim and desire by Letters Patent to secure is:

1. A lacing stud in two parts, namely, a base and a hook movably mounted thereon, said hook comprising a substantially U-shaped portion having an arm normally separated from said base by a space through which a lacing may be introduced into said hook, the whole of said hook being adapted to be moved bodily relatively to said base by said lacing to close said space.

2. A lacing stud in two parts, namely, a base and a hook slidably mounted thereon, said hook comprising a substantially U-shaped portion having an arm normally separated from said base by a space through which a lacing may be introduced into said hook, the whole of said hook being adapted to be moved bodily relatively to said base by said lacing to close said space.

3. A lacing stud in two parts, namely, a base and a hook mounted thereon to slide in a curved path, said hook comprising a substantially U-shaped portion having an arm normally separated from said base by a space through which a lacing may be introduced into said hook, the whole of said hook being adapted to be moved bodily relatively to said base by said lacing to close said space.

4. A lacing stud in two parts, namely, a base and a hook slidably mounted thereon, said hook comprising a substantially U-shaped portion having two arms, one of said arms being slidably mounted on said base and the other of said arms being normally separated from said base by a space through which a lacing may be introduced into said hook, the whole of said hook being adapted to be moved bodily relatively to said base by said lacing to close said space.

5. A lacing stud in two parts, namely, a base and a hook mounted thereon to slide in a curved path about a center outside of said stud, said hook comprising a substantially

U-shaped portion having an arm normally separated from said base by a space through which a lacing may be introduced into said hook, the whole of said hook being adapted to be moved bodily relatively to said base by said lacing to close said space.

6. A lacing stud comprising a base, a hook slidably mounted thereon, said hook comprising a substantially U-shaped portion having an arm normally separated from said base by a space through which a lacing may be introduced into said hook, the whole of said hook being adapted to be moved bodily relatively to said base by said lacing to close said space, and a stop adapted to limit the extent of movement of said hook.

7. A lacing stud comprising a base and a hook slidably mounted thereon, said hook comprising a substantially U-shaped portion having two arms, one of which is normally separated from said base by a space through which a lacing may be introduced into said hook, the whole of said hook being adapted to be moved bodily relatively to said base by said lacing to close said space, and a projection on said base extending over the other of said arms.

8. A lacing stud comprising a base and a hook slidably mounted thereon, said hook comprising a substantially U-shaped portion having two arms, one of which is normally separated from said base by a space through which a lacing may be introduced into said hook, the whole of said hook being adapted to be moved bodily relatively to said base by said lacing to close said space, and two oppositely located projections on said base extending over the other of said arms.

9. A lacing stud comprising a base having a tubular shank, a hook slidably mounted on said base, said hook comprising a substantially U-shaped portion having two arms, one of which is normally separated from said base by a space through which a lacing may be introduced into said hook, the whole of said hook being adapted to be moved bodily relatively to said space by said lacing to close said space, two oppositely located projections on said base extending over the other of said arms, and two other oppositely located projections on said base extending beneath said other arm.

In testimony whereof I have hereunto set my hand in presence of two subscribing witnesses.

LUTHER B. DAVIS.
